(57) **CLAIM**

The ornamental design for optical measuring instrument, as shown and described.

DESCRIPTION

1. Optical measuring instrument

1.1 : Perspective

1.2 : Front

1.3 : Back

1.4 : Left

1.5 : Right

1.6 : Top

1.7 : Bottom

Reproduction 1.1 perspective view (front, top and left side); reproduction 1.2 front view; reproduction 1.3 rear view; reproduction 1.4 left side view; reproduction 1.5 right side view; reproduction 1.6: top view; reproduction 1.7: bottom view; the thin parallel lines in the reproductions aim to reproduce the relief and not to illustrate an ornamentation of the products.
